DESIGN FOR A HANDBAG OR SIMILAR ARTICLE

Charles G. Lewine, Philadelphia, Pa.

Application October 22, 1940, Serial No. 96,002

Term of patent 3½ years

To all whom it may concern:

Be it known that I, Charles G. Lewine, a citizen of the United States, residing at Philadelphia, in the county of Philadelphia and State of Pennsylvania, have invented a new, original, and ornamental Design for a Handbag or Similar Article, of which the following is a specification, reference being had to the accompanying drawing, forming a part thereof.

Fig. 1 is a front elevational view of a handbag showing my new design; and

Fig. 2 is an end elevational view thereof.

The side and end not shown are substantially the same as those shown.

The dominant features of the design reside in the portions shown in full lines. The dotted lines on the overlapping portions indicate stitching.

I claim:

The ornamental design for a handbag or similar article, substantially as shown and described.

CHARLES G. LEWINE.
